UNITED STATES PATENT OFFICE.

JOSEPH TÖTH, AMBROSIUS BELEZNAY, AND JOHN LIPTAK, OF PITTSBURG,
PENNSYLVANIA.

SPRING BED-BOTTOM.

972,040.

Specification of Letters Patent.

Patented Oct. 4, 1910.

Application filed March 5, 1910. Serial No. 547,488.

To all whom it may concern:

Be it known that we, JOSEPH TÖTH, AMBROSIUS BELEZNAY, and JOHN LIPTAK, subjects of the King of Austria-Hungary, residing at Pittsburgh, in the county of Allegheny and State of Pennsylvania, have invented certain new and useful Improvements in Spring Bed-Bottoms, of which the following is a specification, reference being

had therein to the accompanying drawing.

This invention relates to spring bed bottom, and the object of our invention is to provide a removable spring bed bottom consisting of two sections hinged whereby the sections can be folded to occupy a comparatively small space when removed from the bed.

We attain the above object by providing a spring structure that can be yieldably mounted in the frame of a bed to sustain considerable weight, the spring being preferably made of light and durable metal with the parts thereof assembled to provide a simple and inexpensive construction.

Our invention will be hereinafter considered in detail and then claimed, and reference will now be had to the drawings forming part of this specification, wherein there is illustrated a preferred embodiment of the invention, but it is to be understood that the structural elements thereof can be varied or changed, as to the size, shape and manner of assemblage without departing from the spirit and scope of the invention.

In the drawings:—Figure 1 is a side elevation of a bed provided with a spring bed bottom in accordance with this invention. Fig. 2 is a plan of the same, Fig. 3 is an end view of the spring bed bottom, and Fig. 4 is an enlarged longitudinal sectional view of one of the spring units, and Fig. 5 is a cross sectional view of the same.

A spring bed bottom constructed in accordance with our invention comprises two rectangular sections A and B, each section comprising super-imposed frames and each frame having longitudinal slats 1 and 2, and transverse slats 3. The longitudinal slats 1 are of a greater length than the longitudinal slats 2, and the lower slats 1 are hinged or pivotally connected, as at 4, whereby the sections can be folded together. The longitudinal and transverse slats 1, 2 and 3 are adapted to be riveted or otherwise connected, as at 5, and between the longitudinal slats 1

and 2 of the frames are arranged resilient units comprising bands or rings 6 loosely mounted in channel shaped straps 7 secured to the under face of the slats 1 and 2 of the upper frame and the upper face of the slats 1 and 2 of the lower frame, these straps being arranged with the open ends thereof confronting to form an opening 8 for the band 6.

Between the transverse slats 3 of the upper and lower frames are arranged resilient units, comprising flat springs 9 riveted or otherwise connected, as at 10 to the lower transverse slats 3, these flat springs having the ends thereof curved upwardly to loosely engage in straps 11 carried by the under face of the upper slats 3.

Besides yieldably supporting the upper frames of the sections A and B relatively to the lower frames thereof, we provide additional means for yieldably supporting the spring relatively to the post 12 of a bed. The outer ends of the lower frames of the sections A and B are connected by coiled springs 13 to the post 12, the springs 13 being anchored at a point above the bed spring, as at 14, the said springs 13 cushioning the downward movement of the entire bed spring. An upward movement of the bed spring is retarded by coiled springs 15 secured to the outer ends of the sections A and B and connecting with the feet 16 of the post 12, these two sets of springs 13 and 15 normally supporting the bed spring adjacent to the side rails 17 of the bed.

Having now described our invention what we claim as new, is:

1. A spring bed bottom consisting of a pair of hinged sections each comprising a pair of superposed sets of longitudinally-extending slats with the outer slats of each set of greater length than the others of the set, a pair of superposed sets of transversely-extending slats and with one of the slats secured to a set of longitudinal slats and with the other of the sets secured to the other set of longitudinal slats, the elongated longitudinal slats of each set projecting beyond the inner slats of the transverse sets, resilient elements interposed between the sets of transverse slats and each consisting of a body portion and a pair of curved ends, means for fixedly securing the body portions of said elements to the slats of the lower set of transverse slats, straps secured

to the slats of the upper set of transverse slats and extending around the curved ends of said elements for loosely connecting said ends to the upper set of transversely-extending slats, said straps disposed longitudinally with respect to said bed bottom, vertically-disposed resilient bands interposed between the sets of longitudinal slats and extending at right angles with respect to said elements, 10 transversely-extending straps secured to the inner faces of the slats of each of the sets of longitudinal slats and extending around said bands for loosely connecting them to said slats, combined with means for hinging the 15 elongated longitudinal slats of one section to the other.

2. A spring bed bottom consisting of a pair of hinged sections each comprising a pair of superposed sets of longitudinally-extending slats, a pair of superposed sets of transversely-extending slats and with one of the sets secured to a set of longitudinal slats and with the other of the sets secured to the other set of longitudinal slats, resilient 25 elements interposed between the sets of transverse slats and each consisting of a body portion and a pair of curved ends, means for fixedly securing the body portions of said elements to the slats of the lower set of transverse slats, straps secured to the slats of the upper set of transverse slats and extending around the curved ends of said elements for loosely connecting said ends to the upper 30 set of transverse slats, vertically-disposed resilient bands interposed between the sets of longitudinal slats, straps secured to the inner faces of the slats of each of the sets of longitudinal slats and extending around said bands for loosely connecting them to said slats, combined with means for hinging one section to the other.

3. A spring bed bottom consisting of a

faces of the slats of each of the sets of longitudinal slats and extending around said 40 bands for loosely connecting them to said slats, combined with means for hinging one section to the other.

3. A spring bed bottom consisting of a pair of hinged sections each comprising a 45 pair of superposed sets of longitudinally-extending slats, a pair of superposed sets of transversely-extending slats and with one of the sets secured to a set of longitudinal slats and with the other of the sets secured to the 50 other set of longitudinal slats, resilient elements interposed between the sets of transverse slats and each consisting of a body portion and a pair of curved ends, means for fixedly securing the body portions of said 55 elements to the slats of the lower set of transverse slats, straps secured to the slats of the upper set of transverse slats and extending around the curved ends of said elements for loosely connecting said ends to the upper 60 set of transverse slats, vertically-disposed resilient bands interposed between the sets of longitudinal slats, straps secured to the inner faces of the slats of each of the sets of longitudinal slats and extending around 65 said bands for loosely connecting them to said slats, combined with means for hinging one section to the other.

In testimony whereof we affix our signatures in the presence of two witnesses.

JOSEPH TOTH.
AMBROSIUS BELEZNAY.
JOHN LIPTAK.
